UNITED STATES PATENT OFFICE.

GARRETT B. DOWNS, OF MAUCH CHUNK, PENNSYLVANIA.

AUTOMATIC TOY CRANE.

Application filed April 23, 1924. Serial No. 703,596.

This invention relates to an automatically operating toy crane or derrick.

It is aimed to provide a novel electrically operable toy with a means to reverse the motion to impart movement to the beam or boom similar to an actual boom, a weight or load, an electromagnet means to raise and release the weight, and means to return the weight after release to initial position.

Another object is to provide the construction forming one embodiment as illustrated in accompanying drawings.

Various additional objects and advantages will appear hereinafter from the description following taken in connection with said drawings.

In said drawings:—

Fig. 1, is a view of the toy inside elevation with the beam or boom in an intermediate position,

Fig. 2, is a plan view with the boom in full lines in initial or lower position and in dotted lines in raised position,

Fig. 3, is a side elevation of the electromagnet reverse,

Fig. 4, is a section on line 4—4 of Fig. 1,

Fig. 5 is a schematic view or diagram of the electrical parts, and

Fig. 6, is a detail showing the reversing contacts in the second or different position from Fig. 5.

Like reference characters designate like or similar parts in the different views.

In reducing the invention to practice, a base 10 of suitable shape, size and material, usually wood, has a bearing block 11 of conducting metal secured thereto and insulated therefrom. A vertical shaft 12 has a conical lower end 13, journalled in a conical recess of block 11 as shown and to the lower portion of the shaft which is designated 14 is of conductive metal. Shaft 12 has a trunnion 12^a at its top journalled in one or more bearings or supports 10^a on base 10. A contact arm 15 extends from end 13 and at the limits of rotation of shaft 12 is adapted to engage contacts 16 and 17, (see Fig. 4), fastened by screws 18 and 19 respectively to the base 10. Shaft 12 may swing or rotate to any extent desired depending on the distance between contacts 16 and 17, and for instance to the extent of 180° instead of 90° as shown.

Pivoted to a lug 20 on shaft 12 at 21 is a lifting boom or beam 22. An electro-magnet 23 is suspended from boom 22 by flexible means at 24 and is adapted to attract and lift

a load such as a ball 25 from the position shown in Fig. 1 to an elevated position over a flared receiver 26 of a return chute 27 where the ball is released by means to be later described. Said chute 27 is of tubular material having an inclined arm 28, coils 29 and a base portion 30. The latter portion is open adjacent its outer end and surrounded by a retaining flange 31 for said ball. The ball thus travels from the top through the chute to the bottom thereof in the position shown in Fig. 1.

Any suitable means may be employed for oscillating or rotating shaft 12 to the extent permitted by contacts 16 and 17 and simultaneously move the boom 22 in a vertical plane. For instance an electric motor 32 is mounted on base 10 having its main shaft 33 provided with a suitable gear wheel such as a worm 34 in mesh with a gear wheel 35 rigid on shaft 12. A drum or windlass 36 by means of trunnions 37 is journalled in bearings 38 secured on base 10. Rigid with said drum 36 is a gear wheel 39 which meshes with a gear wheel or worm 40 rigid on shaft 33.

Fastened at one end to drum 36 is a flexible cable 41 which has its other end secured at 42 to beam 22. Said cable is trained over periphery-grooved pulleys as at 43 and 44, journalled respectively on a pin 45 extending from shaft 12 and on a pin 46 mounted by a bracket 47 on base 10.

An electro-magnetic reversing mechanism 48 for the motor 32 is mounted by a plate 49 on base 10. A rocker 50 of insulation is journalled by means of trunnions 51 in bearings 52 on plate 49. Arms 53 extend from rocker 50 and by means of pin and elongated slot connections 54 and 55 are pivoted to movable cores or armatures 56 and 57 within the coils or windings 58 and 59 of electromagnets 60 and 61. Secured to rocker 50 and by the same insulated from each other are contacts 62 and 63 with which spring contacts 64, 65 and 66 coact and which are insulated from each other and mounted on and insulated from plate 49 by a block 67.

The electric circuit through the different parts is established by the following means. Feed wires 68 lead from a suitable source of electricity to wires 69 and 70, if desired through a transformer at 71 which is used when the current supplied as by a house lighting system is of high voltage since my toy will operate on low voltage. A switch 72 may

be provided in wires 69 and 70 with the parts in the position of Fig. 5, the current flows from the source through wire 69, a terminal 73 on bearing 11, shaft 12 at 14, contacts 15 and 16, a wire 74, and winding 58 to wire 70. Thus magnet 60 is energized which attracts armature 56 rocking rocker 50 and energizing contacts 64 with contact 62 and contact 66 with contact 63. From wire 69, the current spreads by wire 75 to the field 76 of motor 32 and then by a wire 77 to contacts 62 and 64 to a wire 78 to the armature 79 of the motor, through a wire 80 to contacts 66 and 63 and by a wire 81 to wire 70. As shaft 12 moves from the position of Fig. 4 to the position of Fig. 5 contact 15 engages contact 17 thus breaking the circuit through magnet 60 and establishing it through magnet 61 as a conductor 82 leads from contact 17 to the winding 59 and a conductor 83, from same to wire 70. Thus magnet 60 rocks element 50 and moves the various contacts into engagement as in Fig. 6 where contact 64 engages contact 63 and contact 66 engages contact 62 whereby the direction of the flow of the current is reversed. Also in the position of Fig. 6 contact 65 engages contact 63 and causes energization of magnet 23 as a conductor 84 connects said magnet and contact 65 and a conductor 85 leads from magnet 23 to terminal 73.

In operation with the ball 25 positioned as in Fig. 1 and magnet 23 in lowermost position, magnet 61 is energized whereby magnet 23 is also energized which attracts said ball. At the same time beam 22 is raised by drum 36 winding up cable 41 and is also turned by the rotation of shaft 12 to a position where ball 25 is over receiver 26 at which time contacts 15 and 17 engage to deenergize magnet 61 and energizing magnet 60. Thus the ball will be released into chute 27 and roll to the position of Fig. 1 and the shaft 12 and beam 22 will be rotated back to initial position, with the drum 36 giving out the cable 41 and beam 22 lowering of its own weight assisted by that of magnet 23. It will thus be seen that the operation of the toy is continuous and automatic in raising the ball or load 25, in releasing it, and with the shaft 12 and beam 22 simu-

lating the operation of corresponding parts 50 of a crane or derrick, and thus form an interesting and fascinating toy.

As merely one embodiment has been illustrated and described it is to be understood that changes in the details may be resorted to within the spirit and scope thereof. 55

I claim as my invention:—

1. An automatic toy simulating a crane or the like having a turnable shaft, a lifting means thereon, means to actuate said shaft 60 and lifting means consisting of an electric motor and electro-magnetic means to establish circuits through said motor for travel of current in reverse directions including a plurality of contacts, and means extending from the shaft in circuit with the electro-magnetic means engaging said contacts to establish the circuits. 65

2. An automatic toy simulating a crane or the like having a turnable shaft, lifting means 70 thereon, means to actuate said shaft and lifting means, the second mentioned means including a motor, means to reverse the direction of flow of current through the motor including a rocker and associated contacts, electro-magnets to actuate said rocker, a contact extending from the shaft, and contacts in circuit with said magnets engageable by the last contact. 75

3. A toy having a base, a shaft rising therefrom and journaled thereon, a load member, a lifting beam for said member having a magnet thereon to engage it, a return chute for said load member, a gear wheel on said shaft, an electric motor having a shaft, a gear wheel 85 on said second shaft in mesh with the first gear wheel, a drum driven from the second shaft, a cable associated with said drum and said lifting member, means to establish electric circuits through said magnet and said motor including spaced contacts on said base, a contact on said shaft engageable with said contacts, and an electromagnetic reversing mechanism in circuit with the motor operable through the coaction of said contacts. 90 95

In testimony whereof I affix my signature.

GARRETT B. DOWNS.
